(57) **CLAIM**

The ornamental design for a stand for holding soldering iron as shown and described.

DESCRIPTION

FIG. 1 is a front perspective view of a stand for holding soldering iron showing our new design;

FIG. 2 is a rear perspective thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the Figures are for the purpose of illustrating portions of the stand for holding soldering iron that form no part of the claimed design.
